UNITED STATES PATENT OFFICE.

OSVALD E. RASMUSSEN, OF WEST HOBOKEN, NEW JERSEY, ASSIGNOR TO WESTERN ELECTRIC COMPANY, INCORPORATED, OF NEW YORK, N. Y., A CORPORATION OF NEW YORK.

AUTOMATIC SWITCH.

1,324,847.

Specification of Letters Patent. Patented Dec. 16, 1919.

Application filed December 1, 1916. Serial No. 134,340.

To all whom it may concern:

Be it known that I, OSVALD E. RASMUSSEN, a subject of the King of Denmark, residing at West Hoboken, in the county of Hudson and State of New Jersey, have invented certain new and useful Improvements in Automatic Switches, of which the following is a full, clear, concise, and exact description.

This invention relates to automatic switches for use in telephone exchange systems, and more particularly to switches of the multiple brush type.

In switches of this type it is customary to first render operative one of a certain set of brushes, after which such selected brush is moved in group steps over the section served by it. At the completion of the group steps, short steps are taken to select a particular terminal set in the selected group.

It is the object of this invention to provide a switch of these general characteristics in which simplicity of structure and operation is attained.

A feature of the present invention is the utilization of a single magnet to control the brush selection, group selection, and individual terminal selection. This magnet controls a double escapement, one of whose pallets may be rendered inoperative at certain times.

The general construction of the contact bank, brush sets and tripping mechanism, may be similar to that disclosed in Patent No. 1,123,696, issued January 5, 1915, to E. B. Craft and J. N. Reynolds.

It is thought that the invention will best be understood from the following detailed description, reference being had to the accompanying drawing.

In the drawing, Figure 1 is a side elevation of the switch showing its general structure; Fig. 2 is a detail view of the controlling magnet and double escapement operated by it, showing also the arrangement of the slots in the driving ribbon; Fig. 3 shows a circuit arrangement suitable for operation with the switch of the present invention.

The switch, as described, is arranged for use as a selector, but may be obviously arranged to perform any of the functions usual to a switch of this type.

The structure of a preferred form of the switch will first be described.

A shaft 1 is mounted in any suitable manner for longitudinal motion, a spiral spring 2 tending to cause upward motion of the shaft. The shaft is provided with a plurality of brush sets 3, there being a brush set for each section 4 of a panel contact bank. These brush sets are normally inoperative but may be made operative by the action of a trip rod 5, carrying tripping fingers 6 and operated by a trip magnet 7. Trip rod 5 and magnet 7 are common to all the brushes of the switch, the brush set to be tripped being determined by the extent of primary motion of shaft 1, as described in the above mentioned patent.

To the lower end of shaft 1 is attached a driving ribbon 8 having two rows of slots punched therein.

An escapement consisting of pallets 9, 10 and 11 is arranged to be operated by a spacing member 12 controlled by the armature 13 of a magnet 14 by means of a bell-crank lever 15.

The lower portion of trip rod 5 carries a U-shaped member 16, so arranged that when the trip rod is rotated, an extension 17 will be thrown into the path of travel of a stud 18 carried by pallet 11.

Referring now to Fig. 2, it will be seen that two series of slots are punched in the driving ribbon 8, the slots 19 being arranged to allow the shaft 1 to be advanced in short steps under the control of the escapement members 9 and 11, while the long slots are arranged to allow the shaft 1 to be advanced in long steps under the control of escapement members 9 and 10. The topmost long slot is equivalent to five of the short slots, the remainder of the long slots being each equivalent to ten of the small slots.

The general operation of the structure is as follows: Upon energization of magnet 14, pallet 9 is withdrawn from the upper slot 19 and pallet 11 will engage the second slot when the ribbon 8 is carried upward by the action of spiral spring 2. Upon deenergization of magnet 14, the ribbon 8 will be advanced a trifle to allow pallet 9 to engage the second slot 19, since the pallet 11 is somewhat shorter than pallet 9. A spring 20

(indicated in Fig. 1) tends to draw pallets 9 and 11 together, and also in a similar manner a spring (not shown) tends to draw pallets 9 and 10 together. In this way the driving ribbon may be advanced in short steps to position a brush set for tripping. Carried by each brush set is a tripping lug 21, it being understood that these lugs 21 are spaced at constantly increasing distances from their respective trip fingers 6, as described in the previously mentioned patent. The trip rod 5 is now rotated to render operative a positioned set of brushes, and in rotating, extension 17 is thrown in the path 15 of stud 18.

When magnet 14 is energized in response to the first of the group selecting impulses, pallet 10 will be thrown forward and engage the bottom of the topmost long slot. Upon deenergization of magnet 14, the ribbon will be advanced upwardly a sufficient amount to allow pallet 9 to engage slot 19', thereby holding the brush set in position below the first group of terminals. It is to be noted 25 that the engagement of stud 18 with extension 17 prevents the operation of pallet 11, which would otherwise interfere and prevent a long step from being taken. The brush shaft 1 is advanced upward in long 30 steps under the control of the escapement as though the escapement were composed only of pallets 9 and 10.

At the conclusion of the group impulses, the trip rod 5 is restored to normal position 35 and the brush shaft 1 is advanced in short steps under the control of the escapement consisting of pallets 9 and 11 as before, since the release of trip rod 5 has allowed pallet 11 to again become operative.

Referring now to Fig. 3, the operation of circuits suitable for use with this switch when operating as a selector is as follows: When the subscriber at substation 31 removes his receiver, his line is extended to the selector whose circuits are shown, in the well-known manner, by the operation of either a line switch or a line finder. A circuit is thereupon completed for stepping relay 32 from grounded battery, left-hand 45 winding of relay 32, side-switch wiper 33 in its first position, through the brushes of the preceding switch and the loop of the calling subscriber, side-switch wiper 34 in its first position, and the right-hand winding of relay 32 to ground. Relay 32 is energized and completes a circuit for slow-release relay 35 from grounded battery, winding of relay 35, to ground at the armature and front contact of relay 32.

60 A series of impulses is now sent to select a brush. Upon the first interruption of the line circuit, relay 32 is deenergized and a circuit for slow-release escape magnet 36 is completed from grounded battery, winding

of magnet 36, armature and front contact 65 of relay 35, armature and back contact of relay 32, to ground. The escape magnet is energized but does not release the side switch. At the same time a circuit is completed for stepping magnet 14 from grounded battery, 70 winding of magnet 14, side-switch wiper 39 and its first contact, armature and front contact of relay 35, and armature and back contact of relay 32 to ground. Upon each deenergization of relay 32, stepping magnet 14 75 is energized and the brush shaft is advanced in short steps under the control of the escapement composed of pallets 9 and 11. At the conclusion of the first series of impulses, relay 32 remains energized for a comparatively long time, whereupon escape magnet 36 is deenergized and releases the side switch into position 2.

In position 2 of the side-switch wipers, trip magnet 7 is energized over a circuit from grounded battery, winding of magnet 7, side-switch wiper 37 in its second position to ground. The operation of magnet 7 trips a positioned set of brushes and throws extension 17 into the path of travel of stud 18 to render pallet 11 inoperative.

Stepping relay 32 is now operated by a second train of impulses over side-switch wipers 33 and 34 in their second positions, to control the group selecting operation of 95 the switch. Relays 35 and 36 are energized as before, as is also magnet 14, but at this time magnet 14 controls an escapement composed of pallets 9 and 10 previously described, and the brush set is advanced in 100 long steps. At the conclusion of this second series of impulses, escape magnet 36 is deenergized as before and moves the side-switch wipers from position 2 into position 3. Trip magnet 7 is thereupon deenergized 105 and returned to its normal position, rendering pallet 11 again operative.

In the third position of the side-switch, magnet 14 interrupts its own circuit at its armature and back contact, this circuit being from grounded battery, winding of magnet 14, side-switch 39 and its third contact, armature and back contact of magnet 14 to ground. Assuming that an idle condition of trunks is represented by the presence of ground on their test terminals, and a busy condition of trunks by the absence of such ground, escape magnet 36 will not be energized until an idle trunk is found, the side switch being so constructed that 110 the magnet 36 will release it from its third to its fourth position upon the energization of the escape magnet. The selected brush set will now be advanced over the terminal sets in the desired group until an idle trunk 115 is found, at which time the presence of ground on the test terminal of such trunk will allow escape magnet 36 to energize and

release the side switch into its fourth position over a circuit from grounded battery, winding of magnet 36, side-switch wiper 38 and its third contact, test brush of the selected set to ground at the terminal of the idle trunk. In the fourth position of the side switch, the operating circuit for stepping magnet 14 is opened and the subscribers' line conductors are extended to a desired trunk over which further connection may be established in any desired manner.

At the conclusion of conversation, ground will be reapplied to the test terminal of the selected trunk by the release of the succeeding switch, at which time a circuit will be completed for down-drive power magnet 40 from grounded battery, winding of magnet 40, off-normal contact 41, side-switch wiper 38 in its fourth position, to ground. Magnet 40, in energizing, completes a locking circuit for itself through its armature and front contact, and at the same time forces the driving ribbon 8 into engagement with the constantly rotating roller 42 to cause the restoration of the switch. When the switch arrives in its normal position, contact 41 will be opened to break the locking circuit of magnet 40.

The side switch is restored in the usual manner by the return of the brush set, and on leaving position 4 maintains ground for the release of the preceding switch over a circuit from ground, armature and back contacts of relays 32 and 35, side-switch wiper 43 in either first, second or third position, to the test conductor of such preceding switch.

What is claimed is:

1. In an automatic switch, a movable shaft, movable contacts carried thereby, a plurality of stationary terminal sets arranged for engagement with said movable contacts, means for causing a primary movement of said shaft, means for causing a secondary longitudinal movement of said shaft, means for causing a tertiary movement of said shaft, and a single magnet to mechanically control all of said movements.
2. In an automatic switch, a movable shaft, movable contacts carried thereby, a plurality of stationary terminal sets, a contact bank containing said terminal sets and arranged to be served by said movable contacts, said terminal sets being arranged in sections and groups, means to select a desired section, means to select a desired group, means to select a desired terminal in said selected group, and a single magnet to mechanically control all of said selecting means.

3. In an automatic switch, a movable shaft, a plurality of multiply-connected brush sets carried thereby, a contact bank divided into sections and groups, there be-

ing one of said brush sets per section, said brush sets being normally inoperative with respect to the section served by them, means for rendering a desired brush set operative, means for advancing said operative brush set in long steps, means for advancing said operative brush set in short steps, and a single magnet to control the means for rendering a desired brush set operative and advancing said shaft. 75

4. In an automatic switch, a movable shaft, a plurality of multiply-connected brush sets carried thereby, a plurality of terminal sets, a panel contact bank containing said terminal sets, said bank being divided into a plurality of sections, there being one of said brush sets per section, said brush sets being normally inoperative with respect to the section served by them, means for advancing said movable shaft into a position where a desired one of said brush sets may be made active, means for rendering active said positioned brush set, means for advancing said active brush set in long steps, means for advancing said active brush set in short steps, and a single magnet to control the movement of the shaft during the positioning for brush selection and during said long and short steps. 80 85

5. In an automatic switch, a movable shaft, movable contacts carried thereby, a plurality of stationary terminal sets arranged for engagement by said movable contacts, a magnet, a compound escapement controlled thereby, and means including said magnet and escapement for causing primary, secondary and tertiary movements of said shafts. 100

6. In a selective switch, a movable shaft, movable contacts carried thereby, a plurality of stationary terminal sets arranged for engagement by said movable contacts, a magnet, a compound escapement controlled thereby, and means including said magnet and escapement to control three selective movements of said shaft. 105 110

7. In a selective switch, a movable shaft, movable contacts carried thereby, a plurality of stationary terminal sets arranged for engagement by said movable contacts, a magnet, a compound escapement controlled thereby, said escapement consisting of a plurality of pallets, and means including said magnet and escapement to control three selective movements of said switch, certain of said pallets being inoperative during certain of said selective movements. 115 120

8. In an automatic switch, a movable contact carrying shaft, a plurality of sets of stationary contacts arranged for engagement with the contacts on said shaft, means for causing a primary movement of said shaft, means for causing a secondary longitudinal movement of said shaft, means for causing a tertiary movement of said shaft, 125 130

and a single means to control all of said movements.

9. In an automatic switch, a movable contact carrying shaft, a plurality of sets of stationary contacts arranged for engagement with the contacts on said shaft, means for causing a primary movement of said shaft, means for causing a secondary move-

ment of said shaft, means for causing a tertiary movement of said shaft, all of said movements being longitudinal, and a single means to control all of said movements.

In witness whereof I hereunto subscribe my name this 28th day of November, A. D. 1916.

OSVALD E. RASMUSSEN.
